UNITED STATES PATENT OFFICE.

HARRY T. SCOTT, OF LOS ANGELES, CALIFORNIA.

PHONOGRAPH-REPRODUCER.

1,040,032.

Specification of Letters Patent.

Patented Oct. 1, 1912.

Application filed November 21, 1911. Serial No. 661,485.

To all whom it may concern:

Be it known that I, HARRY T. SCOTT, a citizen of the United States, residing at Los Angeles, in the county of Los Angeles, State 5 of California, have invented new and useful Improvements in Phonograph-Reproducers, of which the following is a specification.

This invention relates to acoustic devices in general and to a phonograph reproducer 10 in particular; and it has to do with certain improvements which render the reproducer more simple in construction and capable of giving better, cleaner and finer results than has heretofore been possible.

15 The prime object of my present invention is the elimination of all looseness of the working parts of a reproducer, together with the provision of a mechanism of such character that the reproducing point is allowed free movement in every direction. 20 Following this primary object, my invention (as applied to the form of reproducer in which the stylus or reproducing point is mounted on a stylus plate and the stylus 25 plate is in turn mounted on the sound box or other stationary frame) consists in a novel mounting for the stylus plate upon the sound box or stationary frame and in a novel mounting of the stylus upon the 30 stylus plate. Broadly considered, the stylus may be mounted upon the stylus plate in any desired manner; my broader conception of invention including only my novel method of mounting the stylus plate, or other equivalent member which carries the stylus mounted thereon in any desired manner, upon the stationary box or frame. And this 35 method of mounting the stylus plate, fundamentally comprises what I term a single 40 point suspension, the stylus plate only having a single point of engagement with the stationary supporting member and being more or less perfectly balanced on that point of engagement. In order to rotate the 45 stylus plate about its vertical axis determined by this point of engagement, I employ a torsion spring which is attached to the stylus plate directly beneath the point of support and which acts about the vertical axis therethrough; and this same torsion spring also acts as a tension spring, if desired, to pull the stylus plate down into position so that it will not leave its point of support. The amount of tension 50 depends entirely upon the weight of the stylus 55

plate itself. If the stylus plate is constructed rather heavily, its own weight is sufficient to hold it in place; if it is constructed more lightly, then the tension spring will be utilized.

60 The above outlined single point suspension of the stylus plate will be seen to eliminate all looseness and at the same time allow the stylus plate free movement in every direction. My method of mounting the stylus 65 on the stylus plate also eliminates all looseness at that point. Preferably the stylus is provided with a vertical axis which rests in semi-cylindrical depressions in the stylus plate, and a small spring is utilized to press 70 the axis into the depressions and hold it accurately in position.

75 There are other features of construction and combination which I wish to emphasize along with those above outlined, and which are more fully explained in the following specification and illustrated in the accompanying drawings, in which:

Figure 1 is a plan view of my improved device. Fig. 2 is a front elevation of the 80 same. Fig. 3 is a side elevation of the same. Fig. 4 is an enlarged horizontal section taken on line 4-4 of Fig. 2. Fig. 5 is an enlarged vertical section taken on line 5-5 of Fig. 2. Fig. 6 is an enlarged section 85 taken on line 6-6 of Fig. 2. Fig. 7 is a vertical section taken on line 7-7 of Fig. 4. Fig. 8 is a section taken on line 8-8 of Fig. 7. Fig. 9 is an enlargement of the portion of Fig. 2 showing the mounting of 90 the stylus on the stylus plate. Fig. 10 is an enlarged cross section of the sound box of my improved device. Fig. 11 is a perspective view of a retaining ring for holding the vibrating diaphragm in the sound box. 95 Fig. 12 is a section taken on line 12-12 of Fig. 6. Fig. 13 is a view similar to Fig. 1, showing a modified form of stylus plate mounting. Fig. 14 is a front elevation of the same. Fig. 15 is an enlarged detail section taken on line 15-15 of Fig. 14. Fig. 16 is a section taken on line 16-16 of Fig. 15. Fig. 17 is an enlarged detail taken as indicated by line 17-17 of Fig. 14.

100 In the drawings 5 designates a suitable upright supporting post which is adjustably mounted in a sleeve 6, so that the post may be moved vertically and rotated horizontally. The lower end of sleeve 6 is split at 7 and a small clamp 8 surrounds the sleeve 110

and serves to clamp it tightly about the upright 5. Upright 5 carries on its upper end a plate 10 to which a sound box 12 is secured, the box 12 being of ordinary construction except that I may vary the proportions to suit my own peculiar mechanism. Within this sound box 12 there is contained a diaphragm 13 of any desired material and formation, and the circular 10 edge of the diaphragm is held between two rings 14 and 15 having inclined surfaces adjacent to each other and engaging with the peripheral portions of the diaphragm. Ring 14 is preferably solid while ring 15 is 15 preferably divided at 16, as is best shown in Fig. 11; so that the ring 15 may be forced down on the diaphragm and force the diaphragm into the configuration shown, the ring 15 expanding 20 slightly while being forced down along the inclined face of the two rings and pulling the edge of the diaphragm out with it, thus imparting to the diaphragm a tension in a radial direction. The ring 15 is held in 25 place by means of a screw threaded ring 17 which is screwed into the sound box in the ordinary manner. The sound box itself is held on plate 10 by screws 18 or by any other suitable holding means. The dia- 30 phragm 13 has a connecting wire 19 which serves to connect with the stylus lever 20.

I have shown a stylus plate 30 which has the usual circular portion 31 immediately before the sound box 12 and which has an 35 extension 32 carrying an adjustable counter-balance 33 on its end. At a point where the extension 32 joins the circular portion 31 there is provided an opening 35. A supporting pin 36 is mounted in a vertical position in the stylus plate and has a pointed end which, when counter-balance 33 is properly adjusted, is as closely as possible coincident with the center of gravity of the 40 whole stylus plate. In order to insure good 45 results from the reproducer, this condition must be approximately fulfilled; although variation of this point from the center of gravity along a vertical line therethrough does not impair the working quality as 50 much as does displacement along a horizontal line through the center of gravity. The point of pin 36 rests in a shallow pointed depression 37 in a member 38 which is solidly mounted in a portion of box 12; but 55 this member 38 may be mounted in any other stationary part of the mechanism. Immediately below the point of suspension of the stylus plate there is secured a pin 40 around which a torsion and tension spring 60 41 is soldered or otherwise secured. This spring 41 typifies, in the preferred form of device, any tension and torsion means and extends vertically downwardly directly beneath the point of suspension of the 65 stylus plate and is secured at its lower end

to a vertical pin 42. This pin 42 passes through the end of an arm 43 and the pin is provided with an enlarged portion 44 of polygonal cross section which engages in an aperture 45 of similar section so that the pin 42 is prevented from turning. A small thumb nut 46 provides means for pulling pin 42 downwardly so that it may be rotated to put any desired torsion on the spring 41.

Spring 41 tends to move the stylus plate in the direction indicated by the arrow in Fig. 1; and the plate is prevented from moving excessively in that direction by means of a link 50 which passes around a pin 51 in the end of the stylus plate. This link 50 passes through the box 12 and is moved longitudinally from its rear end through the medium of an arm 52 mounted on the upper end of a vertical rod 53. This rod 53 is operated to move the stylus plate into and out of operative position; but the mechanism to effect this movement need not be entered into in this specification. Stylus 20 is pivotally mounted on a vertical axis 60 which is mounted on the stylus plate and held in engagement therewith in a novel manner. The stylus 20 moves about its pivot in a horizontal direction, and the stylus point 20^a engages with a cylindrical record 61 which has its axis in a vertical position. Axis 60 of the stylus rests in two small approximately semi-cylindrical vertical grooves in the stylus plate, these grooves being designated by the numeral 65. It is 100 desired that these grooves be not of great length, as it is more easily possible to make the axis 60 fit accurately when the grooves are short. But it is desirable to make the axis 60 somewhat longer than the grooves 105 would provide for; and so the grooves are limited on their outer ends by apertures 66 which may pass completely through the stylus plate. The grooves are limited on their inner ends by the slot 67 in which the stylus 20 is placed, this slot 67 connecting with an enlarged aperture 68 in which the end of stylus 20 is located and through which the connection 19 passes. The axis 60 is held in place in the semi-cylindrical 115 grooves 65 by means of a small double ended spring 70 secured by a screw 71 to the stylus plate. The ends of this spring press in notches 70^a on the axis 60 and press it into the grooves; the engagement of the spring with the notches preventing endwise movement of the axis 60. The axis fits into the grooves accurately so that there is no looseness whatever. The stylus 20 is sufficiently loose in slot 67 to prevent it engaging 120 with the edges of the slot.

With the stylus plate hanging in a vertical plane, as illustrated, and swinging horizontally into and out of engagement with the record, it will be seen that no part 130

of the weight of the stylus plate comes on the record at all. The only force tending to engage the stylus plate or the stylus with the record is the torsional force of the spring 41; and this may be adjusted as is desired. In the form of reproducer in which the weight of the stylus plate is supported by the stylus resting upon the record, the weight of the stylus plate is limited very closely. On 10 the weight and inertia of the stylus plate depends the efficiency of transmission of the sound vibrations from the stylus point to the vibrating diaphragm in the sound box. In my construction I may increase the 15 weight of the stylus plate, and therefore its inertia as to movement about its single point of support, very greatly; and I am consequently enabled to decrease the vibrational movement of the stylus plate, to render the 20 stylus plate more nearly stationary while still movable to follow any variations in the surface of the record due to eccentricity, and thus keep the vibrations more completely concentrated in the stylus and the 25 connecting mechanism to the vibrating diaphragm. This is a feature of prime importance; and my method of single point suspension and of holding the stylus plate in place by the torsion and tension spring 30 enables me to employ the methods and mechanisms just described.

In the foregoing described mechanism it will be seen that I have completely avoided all difficulties of the stylus point following 35 any radial variation in the record, allowing the stylus point to move to and from the record without any interference by the weight of the stylus plate; in fact, the greater weight and inertia of the stylus 40 plate rendering the operation more perfect. I also have devised a special means for minimizing or entirely obviating any tendency of the stylus point to vertical movement; that is, any tendency to movement along 45 the record and parallel with its axis.

In the foregoing described mechanism it will be seen that the attachment of the spring 41 at a point at some distance from the point of support 35 will cause a certain 50 tendency of the stylus plate to come back to the position shown in Fig. 2 if either end is raised or depressed. Thus, should the stylus point be lowered by any vertical movement of the record groove, there is 55 immediately called into play a force tending to move the stylus point back to its horizontal position opposite the point of support 35. This vertical movement may be caused by variation in the sound groove on 60 the record, or, as is more frequently the case where the record is supported vertically, it is caused by the gradual settling of the record on its cone shaped mandrel. There may then be some tendency for the 65 stylus point to jump from one groove into

another and thus cause repetition or skipping in the reproduction. To obviate these possible difficulties I have shown a method whereby the spring 41 may be attached to the stylus plate at a point above or below the point of support 35 and as close thereto as is desired. By appropriately placing the point of attachment of the spring 41 the tendency to move the stylus point to its normal position may be lessened or increased. This mechanism is shown in Figs. 70 13 to 17. Here I have shown the aperture 35^a in the stylus plate bridged by two webs 100 having pivot depressions 101 therein. In the present case I have shown these pivot 75 depressions as being exactly opposite the point of support where pointed pin 36^a rests in depression 37^a in member 38^a. Member 38^a is bent so as to enter into the space between the two webs 100; but this 80 construction may be as desired. Engaging with pivot depressions 101 is a pair of pivot points 102 and 103 mounted on a yoke 104. Pivot point 103 is adjustable so that the 85 bearings may be kept in best working order. The spring 41^a is attached to the lower end of yoke 104 so that both torsion and tension may be transmitted therethrough. Where the spring is thus attached to the stylus 90 plate it will be seen that the downward tension of the spring will have absolutely no 95 tendency whatever to move the stylus plate in a vertical plane about its point of support, the only tendency of the downward pull being to hold the pin 36^a in its depression 37^a. If the pivot points 102 and 103 are placed slightly below the point of support, then there will be only a slight 100 tendency to bring the stylus point back to its normal position. The pivot points may be placed above the point of support if desired; and this placement may be used to 105 counteract the tendency of the connecting wire 19^a which always tends to bring the stylus plate back to its normal position, co-acting with spring 41 acting in torsion. The lengthening of this connection 19^a, as 110 shown in Fig. 13, tends to lessen the tendency for this action to bring the stylus plate back to its normal position as regards vertical movement. With this mechanism it will be seen that the relative positions of the point of support of the stylus plate and the point of attachment of spring 41^a may 115 be varied to suit any particular condition; and on account of this variability I do not wish to limit myself to any specific point of connection of the spring to the stylus plate. 120

In Fig. 17 I have shown a modified means of securing the lower end of spring 41^a, consisting of a small rod 120 to which the lower end of the spring is attached for both torsion and tension, this rod being clamped in the split end of bar 43^a by means of a small thumb screw 121. A small thumb 130

nut 122 on the lower end of the rod 120 provides means for turning the rod and for moving it longitudinally as desired.

Having described my invention, I claim:

5. 1. In an acoustic mechanism, a stationary frame, a vibrating member thereon, a stylus plate, a stylus thereon and connected to the vibrating member, a supporting member on the frame, a supporting member on the stylus plate and engaging the first named supporting member at a single point, said point of engagement being approximately coincident with the center of gravity of the stylus plate, and a torsion and tension member 10 acting downwardly and rotatively on the stylus plate along and about a vertical line passing through said point of engagement.
15. 2. In an acoustic mechanism, a stationary frame, a vibrating member thereon, a stylus plate, a stylus thereon and connected to the vibrating member, a supporting member on the frame, a supporting member on the stylus plate and engaging the first named supporting member at a single point, said point of engagement being approximately 20 in a vertical line through the center of gravity of the stylus plate, and a torsion and tension member acting downwardly and rotatively on the stylus plate along and about the said line determined by the center of gravity.
25. 3. In an acoustic mechanism, a stylus plate mounting comprising a stationary member, and a supporting member on the stylus plate and engaging the stationary member at a single point, said point of engagement being approximately 30 on a vertical line determined by the center of gravity of the stylus plate.
35. 4. In an acoustic mechanism, a stylus plate mounting comprising a stationary member, a supporting member on the stylus plate and engaging the stationary member at a single point, said point of engagement being approximately 40 on a vertical line determined by the center of gravity of the stylus plate, and a torsion and tension member acting on the stylus plate about and along the said line determined by the center of gravity.
45. 5. In an acoustic mechanism, a stylus plate mounting comprising a stationary member, a supporting member on the stylus plate and engaging the stationary member at a single point, said point of engagement being approximately 50 on a vertical line determined by the center of gravity of the stylus plate, and a torsion and tension spring attached to the stylus plate and extending downwardly directly beneath the said point of engagement and being stationarily fixed on its lower end.
55. 6. An acoustic mechanism, comprising a stationary sound box, a vibrating member therein, a stylus plate, a mounting for the 60 stylus plate on the sound box and comprising

ing coöoperating members on the box and plate, the plate member resting on the box member at a single point of engagement, torsion and tension means acting on the plate about and downwardly along the vertical line passing through the said point of engagement, a stylus pivotally mounted on the plate, and connecting means between the stylus and the vibrating member in the sound box.

70 75 80 85 90 95 100 105 110 115 120 125 130

7. An acoustic mechanism, comprising a stationary sound box, a vibrating member therein, a stylus plate, a mounting for the stylus plate on the sound box and comprising coöoperating members on the box and plate, the plate member resting on the box member at a single point of engagement, torsion and tension means acting on the plate about and downwardly along the vertical line passing through the said point of engagement, a stylus having a vertical axis, the stylus plate having depressions adapted to receive the stylus axis, spring means for holding the stylus axis in said depressions, and a connection between the stylus and the vibrating member in the sound box.

8. In an acoustic mechanism, a stylus plate mounting comprising a stationary member, a supporting member on the stylus plate and engaging the stationary member at a single point, said point of engagement being approximately at the center of gravity of the stylus plate, and a torsion and tension spring attached to the stylus plate approximately at the center of gravity of the stylus plate.

9. In an acoustic mechanism, a stylus plate mounting comprising a stationary member, a supporting member on the stylus plate and engaging the stationary member at a single point, said point of engagement being approximately at the center of gravity of the stylus plate, a yoke pivotally attached to the stylus plate horizontally opposite the center of gravity thereof, and a tension and torsion spring attached to the lower part of the yoke.

10. In an acoustic mechanism, a stylus plate mounting comprising a stationary member having a pivot depression therein, a pin on the stylus plate having a pointed end resting in said depression, the point of support thus formed approximately coinciding with the center of gravity of the stylus plate, a yoke pivoted to the stylus plate on a horizontal axis passing approximately through said center of gravity, the yoke depending below the stylus plate, and a torsion and tension spring attached to the lower portion of the yoke and acting in torsion and tension about and along a vertical line passing through the axis on which the yoke is connected to the stylus plate.

11. In an acoustic mechanism, a stylus plate mounting comprising a stationary member having a pivot depression therein, a

pin on the stylus plate having a pointed end resting in said depression, the point of support thus formed approximately coinciding with the center of gravity of the stylus plate,
5 a yoke pivoted to the stylus plate on a horizontal axis passing approximately through said center of gravity, the yoke depending below the stylus plate, and a torsion and tension spring attached to the lower portion of
10 the yoke and acting in torsion and tension about and along a vertical line passing through the point of support of the stylus plate.

12. In an acoustic mechanism, a stationary frame, a stylus carrying member, co-operating supporting members on said member and the frame and having but a single point of contact, and a torsion spring attached to the said member and acting about
15 20 a vertical axis determined by said point of contact.

13. In an acoustic mechanism, a stationary frame, a stylus carrying member, co-

operating supporting members on the said member and frame and having but a single 25 point of contact approximately in a vertical line through the center of gravity of said member, and a torsion and tension spring acting downwardly and rotatively on said member approximately along and about the 30 said line determined by the center of gravity.

14. In an acoustic mechanism, a stationary member, a stylus plate, co-operating support members on the stationary member and plate engaging each other at but a single 35 point of contact, and yielding means acting along the vertical axis determined by said point of contact to move the stylus plate horizontally about the said point of support.

In witness that I claim the foregoing I 40 have hereunto subscribed my name this 13th day of November 1911.

HARRY T. SCOTT.
